US00D778161S

(12) **United States Design Patent** (10) **Patent No.:** **US D778,161 S**
(45) **Date of Patent:** **** Feb. 7, 2017**

(54) **PACKAGING**

(71) Applicant: **Apple Inc.**, Cupertino, CA (US)

(72) Inventors: **Alissa Anderson**, San Francisco, CA (US); **Jonathan Berk**, Mountain View, CA (US); **Margaret Madigan Burke**, Sunnyvale, CA (US); **Jack Wanderman**, San Francisco, CA (US); **Kevin Scott Fetterman**, Los Altos, CA (US)

(73) Assignee: **APPLE INC.**, Cupertino, CA (US)

(**) Term: **14 Years**

(21) Appl. No.: **29/519,811**

(22) Filed: **Mar. 9, 2015**

(51) LOC (10) Cl. **09-07**

(52) U.S. Cl.

USPC **D9/456**

(58) **Field of Classification Search**

USPC D9/737, 721, 748, 749, 756, 501, 414, D9/424, 434, 455–457, 759; D3/304, 295; D7/550.1, 553.1–553.8, 581, 586, 587; D24/227, 229, 230; 428/131; 229/120; 220/4.21; 206/733, 528, 486, 485, 427, 206/461, 828

CPC A61B 10/0096; A61B 50/20; A61B 50/30; A61C 2202/00; A61J 1/16; A63B 57/203; B25H 3/003; B44D 3/125; B65D 73/0092; B65D 81/025

See application file for complete search history.

(57) **CLAIM**

The ornamental design for packaging, as shown and described.

DESCRIPTION

FIG. 1 is a top front perspective view of packaging showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top front perspective reference view thereof showing our new design in an environment in which it may be used.

The dashed broken lines in the figures show portions of the packaging and environment that form no part of the claimed design.

The dot-dash broken lines in the figures show boundaries that form no part of the claimed design.

(Continued)

The shade lines in the figures show contour and not surface ornamentation.

1 Claim, 5 Drawing Sheets
